UNITED STATES PATENT OFFICE

2,573,492

DEFLECTOR FOR CUPOLAS

John N. Richardson, Port Washington, Wis., assignor to Modern Equipment Company, Port Washington, Wis., a corporation of Wisconsin

Application May 19, 1949, Serial No. 94,061

7 Claims. (Cl. 214—18)

1

This invention relates to improvements in deflectors for cupolas.

In foundries, charging buckets having vertically movable, cone-shaped bottoms, are commonly utilized for the purpose of delivering charges of pig iron, coke and lime into a cupola. These buckets are customarily moved into the door or receiving opening of the cupola by means of a skip carriage or movable beam, there being mechanism in connection with each type of transporting device for moving the bucket into discharge position, and for then discharging the contents by mechanically lowering the cone-shaped bottom.

Where the conventional, large cone-type of bucket is used, all of the charge must fall outwardly of the periphery of the bucket, with the result that the charge is thrown against the sides of the cupola, from which it bounces back toward the center.

In cupolas where, as a result of the above described action, the iron and coke of the charge are solidly packed in the center, the air entering the bottom of the cupola passes upwardly through the more loosely packed portions adjacent the side wall. This is because the rising air follows the path of least resistance. Poor combustion at the center of the cupola, and chilling of the falling slag follows. Such chilling of the slag eventually blocks up the tuyères, and may, after a sufficient time, entirely stop the melting operation. It is therefore important that the charge be deposited in the cupola in a manner so that the center of the charge in the cupola is less dense than the surrounding portions of the charge, thereby causing the air flowing upwardly from the tuyères adjacent the wall of the cupola to flow toward the center thereof rather than up the sidewall, thereby causing uniform air distribution throughout the cupola and insuring efficient operation.

Conventional, large cone-type buckets require that a substantial clearance be provided between the periphery of the cone and the inner sidewalls of the cupola in order that the charge have sufficient room to pass downwardly around the large bottom cone. Thus, buckets having cone bottoms are particularly undesirable when used with cupolas of small diameter. As a result, it has heretofore been proposed to use a tilttable bucket with small cupolas for dumping the charge into the cupola.

Tilttable buckets are objectionable because when they are loaded, the coke is usually in a layer on the bottom, and the pig iron is in a layer

2

on the top. Thus, when the bucket is tilted for discharge into the cupola, the top layer of material is all deposited on the far side and the bottom layer of coke is deposited on the near side. 5 This obviously negatives efficient cupola operation.

My Patent No. 2,333,042 discloses an improved type of bucket which has a novel hinged bottom construction and which is particularly well adapted for use in small cupolas. The above-mentioned construction does not have the objectionable features inherent in the tilttable type buckets. However, the condition of density of the charge in the center of a cupola which has been 15 charged with a bucket of the type shown in my prior Patent No. 2,333,042, does not result in as uniform air distribution throughout as might be desired.

It is therefore a general object of my invention 20 to provide a deflector for use in a cupola which will distribute the charge dropped into said cupola from a charging bucket in a manner such that the density of the portion of charge in the center of the cupola is less than that of the portions adjacent the wall of the cupola.

Another object of the invention is to provide a deflector which has a substantially conical upper surface, which is positioned centrally of the cupola, and which is of a size to provide adequate 30 room between it and the cupola side wall through which the falling charge can pass.

A further object of the invention is to provide a deflector of the class described which is adapted to be permanently mounted within a cupola.

35 A further object of the invention is to provide a deflector of the class described which is mounted on a rotatable horizontal beam member to permit rotation of said deflector and beam approximately 180° after each charging operation and thereby remove any portion of the charge which may have come to rest thereon during the charging operation.

A further object of the invention is to provide a deflector assembly wherein the deflector and 45 the supporting beam therefor are cooled by fluid circulated therethrough.

A further object of the invention is to provide a deflector of the class described which may be supported by a beam, the latter extending diametrically across the cupola and being supported either at both ends or on a cantilever type beam extending radially into the cupola from one side only.

A further object of the invention is to provide 55 a deflector of the class described which is strong

and durable, which is relatively simple in construction and easy to manufacture, and which is otherwise well adapted for the purposes described.

With the above and other objects in view, the invention consists of the improved cupola deflector, and all of its parts and combinations, as set forth in the claims, and all equivalents thereof.

In the drawings accompanying and forming a part of this specification, wherein are shown two forms of the invention, and wherein the same reference characters indicate the same parts in all of the views:

Fig. 1 is a side elevational view of the main form of the invention showing the device mounted in a cupola, parts of the cupola and of the deflector assembly being broken away and shown in section;

Fig. 2 is a horizontal sectional plan view taken approximately along the line 2-2 of Fig. 1;

Fig. 3 is a fragmentary end view taken approximately along the line 3-3 of Fig. 1;

Fig. 4 is a fragmentary vertical sectional view taken approximately along the line 4-4 of Fig. 1; and

Fig. 5 is a view similar to Fig. 1 and showing a modified form of the invention, parts being broken away for clarity.

Referring to Fig. 1 of the drawing, the numeral 10 indicates a cupola having a steel shell 11 and having a lining of refractory material 12. The cupola 10 is formed with a pair of diametrically oppositely disposed apertures 13 and 14 therethrough. The apertures are spaced below the charging position of the cupola charging bucket (not shown) and are spaced above the bed in the cupola.

Mounted on suitable supports adjacent the apertures 13 and 14 respectively are bearing members 15 and 16 respectively. Portions of the bearings 15 and 16 may project into the apertures 13 and 14 as shown. Rotatably supported at each end in the bearings 15 and 16 is a beam member 17 which may be formed of three sections, i. e., an intermediate section 18, a journal 19 at one end, and a journal 20 at the opposite end. The journals 19 and 20 respectively are mounted in the bearings 15 and 16, and each extends outwardly from the bearing in which it is mounted.

Formed as an integral part of and positioned midway of the length of the section 18 of the beam 17 is a deflector 21 having an upper conical surface 22 and having a lower frusto-conical surface 23 (see Fig. 4). The deflector 21 is formed with a pair of frusto-conical chambers 24 and 25 which are separated by a baffle 26. The intermediate section 18 of the beam 17 is formed of a relatively narrow box-section having a baffle 27 running longitudinally thereof to separate it into an upper chamber 28 and a lower chamber 29 (see Figs. 1 and 3).

The journal 19 of the beam 17 is formed with a pair of longitudinal bores 30 and 31 which communicate respectively at their inner ends with the chambers 28 and 29 of the intermediate section 18. The baffle 27 is formed, at the end adjacent the journal 20, with an aperture 32, and the deflector 21 is formed with diametrically opposed apertures 33 and 34 which afford communication between the chamber 25 and the chambers 28 of the section 18. The deflector 21 is also formed with diametrically opposed apertures 35 and 36 which afford communication between the chamber 24 and the chambers 29 of the section 18. The outer ends of the bores 30 and 31 in

the journal 19 are adapted to receive conduits 37 and 38 respectively.

The conduit 37 leads to a suitable source of circulating coolant such as the city main 47 through a suitable shut-off valve 48. The conduit 38 may, if desired, lead to a sewer.

Fixed to the journal 20 outwardly of the bearing 16 is a collar 39 formed with an arm 40. A fluid operated ram 41 is mounted adjacent the outer end of the journal 20, as shown in Figs. 1, 2 and 3, with the cylinder 42 thereof pivotally mounted, as at 43, and with the piston rod 44 thereof pivotally connected to the arm 40, as at 45. The axis of the ram 41 and of the arm 40 are preferably normally disposed at a slight angle, as shown in Fig. 3. The ram 41 may be connected, as shown diagrammatically in Fig. 3, to a suitable source of fluid pressure 49, such as a tank containing air under pressure, through conduits 50 and 51, there being a three-way valve 52 which has a port 53 vented to the atmosphere.

In operation, cooling water flows in through the conduit 37 and the bore 30 into the lower chamber 28 of the beam 17. The water then flows, as indicated by the arrows, through the aperture 33, chamber 25, aperture 34, chamber 28, aperture 32, and thence into the upper chamber 29. The water flows back from chamber 29, through the aperture 36, chamber 24, aperture 35, chamber 29, bore 31, and out through the conduit 38. Continued circulation of water through the beam 17 and deflector 21 cools said parts sufficiently so that they safely withstand the intensely high temperatures generated within the cupola during operation thereof.

As a charge is dropped from a charging bucket positioned above the deflector 21, a portion of said charge impinges upon the conical upper surface 22 of said deflector and is deflected radially outwardly as it descends within the cupola. The deflector 21 has a cross-sectional area sufficiently small to provide ample room around its periphery for the charge to pass freely between said deflector and the cupola side wall. As a result, the charge is distributed on the bed of the cupola with a central portion of decreased density and optimum conditions of cupola operation are obtained.

After each charging operation the ram 41 is actuated by fluid under pressure, and the piston rod 44 is extended. As this is done, the arm 40 (and hence also the beam 17 and deflector 21) is rotated approximately 180°, as indicated by the dot and dash lines of Fig. 3. This rotation causes any portions of the charge which may have come to rest on top of the beam 17 or deflector 21 to drop off and to fall downwardly onto the cupola bed. The piston rod 44 is then retracted to return the parts associated therewith to their normal positions.

Fig. 5 shows a modified form of the invention wherein a deflector 21' is supported by and is an integral part of a cantilever type beam 17'. The beam 17' is formed with a box-section portion 18' and with a round shaft portion 19'. The section 18' is similar to one half of the beam 17 of the main form of the invention, having a baffle 27' separating it into a lower chamber 28' and an upper chamber 29'.

The shaft 19' is journaled in a pair of spaced bearings 15' and 16' positioned outwardly of the cupola, as shown, and is formed with a pair of longitudinal bores 30' and 31' which communicate at their inner ends with the chambers 28' and 29' of the beam 17'. The deflector 21' is

formed with chambers 24' and 25' separated by a baffle 26'. An aperture 33' provides communication between the chamber 28' of the beam 17' and the chamber 25' of the deflector, and an aperture 35 provides communication between the chamber 29' of the beam 17' and the chamber 24' of the deflector. An aperture 45 in the baffle 26' affords communication between the chambers 24' and 25' of the deflector 21'.

The outer ends of the bores 30' and 31' are adapted to receive conduits 37' and 38' respectively, which are connected to a suitable source of circulating cooling water (not shown). A collar 39' formed with an arm 40' is fixed to the shaft 19' outwardly of the bearing 16', and a ram 41' is connected thereto in the same manner as the ram 41 is connected to the arm 40 in the main form.

The ram 41' is of the double acting type, and is shown diagrammatically in Fig. 5 connected to a gear pump 55 and to a reservoir or sump 56. A pair of three way valves 57 and 58 control the flow of fluid to the ram 41' from the pump 55, and from said ram back to the sump 56. It is apparent that when the valves 57 and 58 are rotated about 45° in a clockwise direction from their shut-off position shown, fluid will flow from the pump 55 through the valve 57 and into the lower end of the ram 41'. This causes said ram to extend upwardly, thereby rotating the beam 17', and also forcing fluid out of the upper end of the ram and back into the sump 56 through the valve 58. A reverse flow of fluid and reverse travel of the ram 41' is accomplished by rotating the valves 57 and 58 to positions about 45° counterclockwise from their shut-off positions shown. This latter fluid flow returns the beam and the deflector 21' to their normal positions shown in Fig. 5.

The deflecting action of the modified form of the invention is substantially the same as that of the main form. In the modified form the coolant flows as indicated by the arrows in Fig. 5. The modified form of the invention offers less obstruction to the downward travel of the dropping charge and, in addition, there is less surface therein which must be cooled by the coolant.

Both forms of the invention cause distribution of the charge over the cupola bed with a central portion of decreased density to thereby maintain the highest possible efficiency in the cupola operation. The ability to tilt the deflector and its supporting beam to thereby dislodge any portions of the charge which may have come to rest thereon is of considerable importance. This feature solves a problem which can be very troublesome in certain instances, such as where the charge being dropped from the bucket contains scrap or the like, particularly where the shape of the scrap makes it susceptible of lodgment on the beam or on the deflector.

Various changes and modifications may be made without departing from the spirit of the invention, and all of such changes are contemplated, as may come within the scope of the claims.

What I claim is:

1. In a charge deflector assembly adapted for use with a cupola, a beam adapted to extend transversely within said cupola and spaced above the bed thereof, and a deflector supported by said beam substantially on the vertical axis of said cupola, said deflector having an upper surface which slopes downwardly and outwardly from a centrally disposed apex, said beam and deflector

being formed with communicating chambers adapted to permit passage therethrough of a circulating fluid coolant, and means for introducing a fluid coolant into said chambers through an end of said beam.

2. In a charge deflector assembly adapted for use with a cupola: a hollow beam adapted to have a portion thereof extending transversely within said cupola and spaced above the bed thereof; bearing means for supporting said beam for rotation on an axis extending longitudinally of said beam; a hollow deflector integral with said beam positioned substantially on the vertical axis of said cupola; generally horizontally extending partitions in said beam and deflector separating said beam and said deflector into upper and lower chambers, the upper beam chambers communicating with the upper deflector chamber and the lower beam chambers communicating with the lower deflector chamber, there being a communication between the beam upper and lower chambers at one end thereof; and cooling fluid inlet and return connections at the opposite end of said beam communicating with the chambers of said beam.

3. In a charge deflector assembly adapted for use with a cupola, a hollow beam adapted to have a portion thereof extending transversely within said cupola and spaced above the bed thereof; bearing means exteriorly of said cupola for supporting said beam for rotation on an axis extending longitudinally of said beam; a hollow deflector integral with said beam positioned substantially on the vertical axis of said cupola and separating said beam into two sections; generally horizontally extending partitions in said beam sections and in said deflector separating said beam sections and said deflector into upper and lower chambers, the upper beam chambers communicating with the upper deflector chamber and the lower beam chambers communicating with the lower deflector chamber, there being a communication between the beam upper and lower chambers at one end thereof; and cooling fluid inlet and return connections at the opposite end of said beam communicating with the chambers of said beam.

4. In a charge deflector assembly adapted for use with a cupola, a hollow beam adapted to have a portion thereof extending transversely within said cupola and spaced above the bed thereof; bearing means for supporting said beam at one end for rotation on an axis extending longitudinally of said beam; a hollow deflector integral with the inner end of said beam positioned substantially on the vertical axis of said cupola; generally horizontally extending partitions in said beam and deflector separating said beam and said deflector into upper and lower chambers, the upper beam chamber communicating with the upper deflector chamber and the lower beam chamber communicating with the lower deflector chamber, there being a communication between the deflector upper and lower chambers; and cooling fluid inlet and return connections at the outer end of said beam communicating with the chambers of said beam.

5. In a charge deflector assembly adapted for use with a cupola: a beam adapted to extend transversely within said cupola and spaced above the bed thereof; a deflector supported by said beam, said beam and deflector being formed with communicating chambers adapted to permit passage therethrough of a circulating fluid coolant; bearing means in which the ends of said beam

are rotatably mounted; and means adjacent one of said bearings for introducing a fluid coolant into said chambers through an end of said beam.

6. In a charge deflector assembly adapted for use with a cupola: a beam adapted to extend transversely within said cupola and spaced above the bed thereof; bearing means for supporting said beam for rotation on an axis extending longitudinally on said beam; a deflector supported by said beam, said beam and deflector being formed with communicating chambers adapted to permit passage of a fluid coolant therethrough; one end of said beam having fluid coolant inlet and return connections communicating with the chambers of said beam.

7. In a charge deflector assembly adapted for use with a cupola: a beam adapted to have a portion thereof extending transversely within said cupola and spaced above the bed thereof; bearing means exteriorly of said cupola in which one end of said beam is journaled for rotation on an axis extending longitudinally of said beam; a deflector supported by said beam, said beam and deflector being formed with a first set of communicating chambers adapted to permit passage of a cooling fluid in one direction therethrough, and said beam and deflector also being

formed with a second set of communicating chambers adapted to permit return flow of cooling fluid therethrough, there being communication between the first set of chambers and the second set of chambers; and cooling fluid inlet and return connections in one end of said beam communicating respectively with said first and second sets of chambers.
